22 Claims. (Cl. 280—168)

ABSTRACT OF THE DISCLOSURE

A switch having flexible insulating walls and internal 10 flexible contacts, either printed circuit or adhesively secured, the switch being extremely thin.

This invention relates to the art of electric switches, and 15 particularly to a switch made by printed circuit techniques.

Electric switches as heretofore manufactured have generally required a great number of separate parts, including biasing springs, and have required individual assembly of such parts. They have not been particularly well adapted to mass production techniques. As will be appreciated, there are many installations in which switches must be sealed. The normal arcing and sparking attendant upon opening and closing electric switches cannot be 20 tolerated in an explosive atmosphere. Conversely, the arcing and sparking of switches causes deterioration of the contact surfaces thereof. It is known that switch life can be prolonged by sealing the switch contacts in an inert atmosphere. As will be appreciated, this also removes danger in an explosive atmosphere. However, prior art techniques for sealing switches have been relatively complicated and difficult, and have added materially to the cost of such switches.

It is an object of the present invention to provide a 35 simplified electric switch.

It is a further object of the present invention to provide an electric switch of extremely simple and inexpensive construction, and particularly one which is well adapted to sealing from the atmosphere.

Yet another object of the present invention is to provide a switch of extremely versatile construction which is readily modified to effect different results and for different installations.

It is further an object of the present invention to provide 45 a switch which is physically safe, i.e., devoid of projecting knobs, levers, etc. for actuation.

Other and further objects and advantages of the present invention will be apparent from the following description when taken in connection with the accompanying 50 drawings wherein:

FIG. 1 is a bottom plan view of one part of a switch constructed in accordance with the present invention;

FIG. 2 is a side view of the structure of FIG. 1;

FIG. 3 is a bottom view thereof;

FIG. 4 is a perspective view thereof on a somewhat enlarged and exaggerated scale;

FIG. 5 is a plan view of the completed switch;

FIG. 6 is a cross-sectional view through the switch as taken along the line 6—6 in FIG. 5;

FIG. 7 is a view similar to FIG. 6 showing the parts in a different position of operation;

FIG. 8 is a view similar to FIG. 5 showing a slightly modified switch;

FIG. 9 is a side view of the switch of FIG. 8;

2

FIG. 10 is a cross-sectional view taken along line 10—10 in FIG. 8;

FIG. 11 is a view similar to FIG. 10 showing the parts in a different position of operation;

FIG. 12 is a view similar to FIG. 11 showing a modification in structure;

FIG. 13 is a view generally similar to FIG. 1 but showing a modified switch;

FIG. 14 is a bottom plan view of the switch of FIG. 13;

FIG. 15 is a longitudinal sectional view as taken substantially along the line 15—15 in FIG. 14;

FIG. 16 is a plan view of the completed switch according to FIGS. 13—15, part being broken away for clarity of illustration;

FIG. 17 is a bottom plan view of the switch of FIG. 16;

FIG. 18 is a cross-sectional view taken substantially along the line 18—18 in FIG. 16;

FIG. 19 is an oblique cross-sectional view as taken substantially along the line 19—19 in FIG. 17;

FIG. 20 is an electric wiring diagram corresponding to the switch of FIGS. 16—19;

FIG. 21 is a longitudinal sectional view through a modified form of the switch before completion of the switch, as taken substantially along the line 21—21 in FIG. 22;

FIG. 22 is a bottom plan view of the partial switch of FIG. 21;

FIG. 23 is a side view of the switch;

FIG. 24 is a top view of the switch of FIG. 23;

FIG. 25 is a cross-sectional view of the switch of FIGS. 23 and 24, being taken substantially along the line 25—25 in FIG. 24;

FIG. 26 is a side view of the switch of FIGS. 23—25 with an electromagnetic operator therefor;

FIG. 27 is a view taken from the right side of FIG. 26;

FIG. 28 is a view similar to FIG. 27 showing a modification adapted for manual operation;

FIG. 29 is a side view of the device of FIG. 28, being similar to FIG. 27 but reversed;

FIG. 30 is a side or sectional view such as of an auto dashboard showing a modification or incorporation of the switch of FIGS. 23—25, etc.;

FIG. 31 is a front view of the switch arrangement of FIG. 30;

FIG. 32 is a view partly in section showing a modification of the invention with electromagnetic operation;

FIG. 33 is a sectional view of a switch generally similar to FIG. 32, but including a flexible tube operating as a peristaltic pump taken substantially along the line 33—33 of FIG. 34;

FIG. 34 is a view at right angles to FIG. 33 as taken substantially along the line 34—34 in FIG. 33;

FIG. 35 is a plan view of a fluid logic circuit using switch constructed in accordance with the principles of my present invention;

FIG. 36 is a sectional view through the fluid logic circuit of FIG. 35 as taken substantially along the line 36—36 therein; and

FIG. 37 is a view partly in section showing switches according to the present invention built into a glove for use in a hostile environment, for example, in an astronaut's glove.

Referring now in greater particularity to the drawings, and first to FIGS. 1—4, there will be seen a square or rectangular plastic sheet or film designated generally by the numeral 50. The plastic material may be any of several

flexible plastics of high strength and substantial flexibility, Mylar, Teflon, Kel-Films and the like being preferred examples, ranging from about 1 mil to 10 mils in thickness. A metal strip 52 is fixed on one face of the plastic sheet or film 50, extending to one margin thereof at 54, and terminating short of the opposite margin thereof at 56. In the present embodiment of the invention, the strip lies along the longitudinal center line of the plastic sheet or film. The metal strip can be adhesively or otherwise secured to the plastic sheet, but preferably it is attached or affixed to the sheet by known printed circuit techniques. In any event, the metal strip 52 is in most instances no thicker than foil, and is readily flexible, as is the plastic sheet.

A rectangular section of the plastic sheet 50 is depressed from the plane thereof as shown at 58 in FIG. 4. This is shown in FIG. 4 as being a rather definite rectangular shape, but as will appear presently, this is not essential, and is not necessarily typical. It is shown this way for convenience in drawing. A section of the conductive strip or foil 52 is displaced with the rectangular section. Typically, the conductive strip or foil is of copper, but other non-ferrous or ferrous metals or other conductive materials are within the purview of the present invention.

As will be seen, the offset section 58 leaves a narrow margin on two sides at 60 and 62 and one end at 64, a larger margin 66 being left on the other end.

The structure as heretofore shown and described, particularly with regard to FIG. 4, comprises a half-switch, hereinafter identified by the numeral 68. Two of the half-switches 68 are relatively turned end-to-end, and are inverted relative to one another, having the concavities formed by the depressed or displaced sections 58 confronting one another and aligned with one another. For the sake of showing the parts as brought together, the numerals heretofore used are applied in FIGS. 5-7 with suffixes -1 or -2 to distinguish one half-switch from the other half-switch. The conductive strips 52-1 and 52-2 are longitudinally aligned with one another, and overlap one another end to end. The margins 60-1 and 62-2 lie face-to-face, as do the margins 60-2 and 62-1. Similarly, the margin 64-2 overlies the margin 66-1, while the margin 64-1 underlies the margin 66-2. All of these margins are secured together, preferably by heat sealing, although a cement or other adhesive is contemplated. As will be appreciated, nitrogen or some other suitable inert gas can be introduced into the space 70 between the two half-switches, thereby producing a pillow type of switch with the contacts in an inert atmosphere. The shaping of the plastic material and the gas trapped therein holds the surfaces or displaced portions 58-1 and 58-2 normally apart from one another as in FIG. 6. This produces a normally open switch 72 shown both physically and electrically in FIG. 6. If a force is exerted on the opposite surfaces of this switch, such as by pinching between the thumb and forefinger, or otherwise, as indicated by the large arrows in FIG. 7, then the overlapping ends of the conductive strips 52-1 and 52-2 are brought into engagement, thus closing the switch. When the pressure is removed, the resiliency of the plastic material and the restoring effect of the gas trapped within the confines of the switch moves the strips out of engagement with one another, thereby re-opening the switch.

It is contemplated that the plastic material would not necessarily have to be shaped to produce the depression or offset at 58 before assembly of the sheets. Rather, the sheets simply could be sealed together at the edges, with gas or air under somewhat greater than atmospheric pressure being introduced between the sheets prior to completion of the sealing thereof. As will be seen in FIG. 5 the end portions of the conductive strip 51-1 and 51-2 are exposed on the surface, and lead wires 74 are soldered or otherwise suitably fixed to the conductive strip for incorporation of the switch 72 in a circuit.

A modification of the switch is shown in FIGS. 9-11.

To avoid multiplicity of description and confusing numbering, the same numerals are used herein with the addition of the suffix *a*. The difference in this instance is that the plastic material is so shaped that the contact strips 52a-1 and 52a-2 initially are in contact, as shown in FIG. 10, thus producing a normally closed switch 72a. It will be apparent that internal pressure slightly less than atmospheric may be used to help hold the contacts in engagement. Lateral pressure as indicated by the larger arrows in FIG. 11 momentarily opens the switch.

The modification of the invention as illustrated in FIG. 12 is similar to that in FIGS. 5-7, similar numerals being used with the addition of the suffix *b*. The only difference is that the switch is not sealed, and a small throttling orifice or hole 76 is provided in one of the offset portions 58b-2 of the plastic material. The interior of the switch obviously has air in it rather than an inert gas. When the switch is closed, some or most of the air is expelled through the orifice 76. When the pressure is released from the switch, air must enter through the orifice 76 to allow the contact strips to move apart, and this delays the re-opening of the switch. The time delay can be pre-determined in accordance with the resiliency of the plastic and the size of the orifice.

The invention as heretofore shown and described has been in the nature of a single-pole, single-throw switch. The invention also contemplates the provision of a multiple-pole, single-throw switch, with the various poles closeable one at a time, or in any desired combination. Such a modification of the switch is shown in FIGS. 13-20. Prolixity of description again is avoided by duplicating numerals, this time with the addition of the suffix *c*. Thus, in FIGS. 13-15, there will be seen three strips 52c of conductive material deposited on the plastic film or sheet 50c. Apertures 80 are provided in the plastic film immediately opposite the enlargements 78 at the ends of the strips 52c for the attachment of lead wires as will be apparent shortly.

Turning to FIGS. 16-20, the switch formed from the half-switches 68c of FIGS. 13-15 is shown. The two switch halves are in concave, face-to-face relation, as with the previous switches, but the two halves are turned 90° relative to one another, rather than 180°. Thus, the conductive strips 52c-1 and 52c-2 cross one another, rather than being in overlapping alignment with one another. Accordingly, there is a total of nine single-pole, single-throw switches. Each of the conductive strips 52c-1 is selectively engageable with any of the three conductive strips 52c-2. As is shown in FIG. 19, pressure is exerted on the opposite faces of the switch to bring only two of the overlapped positions together, as indicated by the large arrows. As will be understood, others of the overlapped contacts could be brought together, and this can be done selectively in single engagements or in multiple engagements, as the occasion may demand.

The embodiment of the invention shown in FIGS. 21-25 is generally similar to those heretofore shown and described, and similar numerals again are used in many instances, this time with the addition of the suffix *d*. Rather than having two like switch sections assembled in confronting relation, in the present embodiment there is only one plastic sheet 50d. This comprises, in the position shown in FIGS. 21 and 22, a left-hand section 82 and a right-hand section 84, lying on either side of a transverse axis or center line 86. The right-hand side or section 84 is provided with a longitudinally extending strip 88 having at the left end thereof a depending enlargement 90. In mirror image relation thereto about the longitudinal center line of the plastic film 50d there is a longitudinally extending strip 92 having an upper projection or enlargement 94, the two enlargements 90 and 94 extending toward one another in spaced relation, and lying completely to the right of the center line 86.

The left-hand plastic section 82 is provided with an enlargement or displaced section 58d of circular nature.

This is provided on the same face thereof as the conductive strips 88 and 92 with a conductive circular area 96.

The plastic material 50d is folded over on itself along the transverse center line 86, the edges being sealed together to form the switch 72d shown in FIGS. 23-25. The ends of the strips 88 and 92 are aligned with the apertures 80d for effecting soldering of lead wires thereto. As will be seen, the conductive circle 96 forms a shorting bar overlying the strips 88 and 92 and including the enlargements 90 and 94 thereof. Pressure on the displaced plastic section 58d as indicated by the large arrow in FIG. 25 moves the circular conductive member or shorting bar 96 into engagement with the strips 88 and 92 to close the switch. The switch in effect is thus a normally open, single-pole, single-throw switch.

A utilization of the switch of FIGS. 21-25 is shown in FIGS. 26 and 27, using electromagnetic operation. A substantially U-shaped frame 98 has a base leg or arm 100 on which the switch 72d is mounted, preferably by means of a suitable adhesive. An opposite arm or leg 102 of the frame carries a solenoid or electromagnet winding 104 having a plunger 106 therein. The plunger has a rounded head 108 engageable with the offset portion 58d to push the shorting bar 96 into switch-closing position. The outer end of the plunger 106 is made of iron or other magnetically attractive material as indicated at 110, the remainder of the plunger being either of non-ferrous metal, plastic, or other non-magnetic material.

As will be apparent, when the coil 104 is energized, the plunger 106 will move to the left, closing the switch as aforesaid. When the coil 104 is de-energized, the resiliency of the plastic, plus the internal pressure of air or gas within the switch returns the plunger to retracted position as the switch opens.

An alternative utilization of the switch 72d is shown in FIGS. 28 and 29. The same U-shaped frame 98 is used as in FIGS. 26 and 27. The difference is that in these figures the switch is manually operated, rather than electromagnetically. To this end, there is an operating lever 112 extending through an orifice 113 in the arm 102 of the bracket 98 and pivotally mounted as on a pin 114. The inner end of the lever 112 is rounded at 116 for engagement with the switch 72d. When the switch is in its normal "off" position, the lever 112 is pivoted or tipped to the dashed-line position shown in FIG. 29. When it is desired to close the switch, the lever is moved to the solid-line position of FIG. 29 wherein the lever is in a dead center position relative to the shorting bar portion of the switch, thereby holding the switch in an "on" position until the lever tipped away from the dead center position, thereby allowing the switch to open.

The practical utilization of a multiplicity of the switches such as 72d is shown in FIGS. 30 and 31. In these figures, an automobile, dash-board or the like is represented at 118. A plurality of switches is formed with a single sheet of plastic 50e to form a switch 72e. The switch 72e will be understood as comprising a plurality of switches similar to the switches 72d in side-by-side relation. Four offset portions 58d are provided. The bottom edge of the folded plastic sheet extends through a slot 120 in the dashboard for accessibility of lead wires behind the dashboard. Four apertures 122 are provided in the dashboard in substantially vertical alignment with the offset portions 58e. Transparent or translucent plastic is used so that light bulbs 124 respectively mounted behind the apertures 122 will shine through the plastic in front of the apertures. Various indicia may be applied to the plastic over the respective openings 122, such for example, as "Lights," "Heater," "Fan," and "Start." Since the switches respectively remain "on" only so long as pushed, as by a direct push exerted by the fingers, it will be understood that the switches may be connected to relays leading to the respective lights or appliances, etc. The relay would be closed in each instance by momentary closure of the respective switch contacts, and would re-

main closed until the switch contacts were again closed by manual pressure.

It will be apparent that the multiple switch 72e requires very little space on the face of the dashboard. Furthermore, being made of plastic it is relatively soft to the touch. There are no projecting parts. Accordingly, not only is one most unlikely to be injured from the switch 72e, in contrast to the switches normally used on auto dashboards, but the switch actually provides a certain amount of padding.

The embodiment of the invention shown in FIG. 32 is designed to produce a buzzer type of action. The switch, hereinafter designated by numeral 72f, comprises a left or base switch half 68f-L having a non-ferrous or non-magnetic contact 52f-L. On the other hand, the right switch half 68f-R is of flexible plastic and the conductive strip 52f-R is of ferrous or other magnetic material. The switch 72f is of the type normally closed, such as previously described in connection with FIGS. 10-12.

A magnetic coil 126 is positioned immediately to the right of the switch 72f, and the coil is connected in series with the switch contacts 52f-L and 52f-R through a battery 128 or other suitable potential source, and also through a normally opened switch 130 which may be of conventional design, or may be similar to one of the switches heretofore disclosed. When the switch 130 is closed the coil 126 is energized. This causes the conductive ferrous strip 52f-R to be pulled toward the coil, thereby opening the circuit. This de-energizes the coil, and the switch 72f returns to its normal closed condition. The coil then is again energized, opening the switch 72f, and establishing a continuous buzzer action as long as the switch 130 is closed. It will be obvious that some utilization circuit or device would also be connected in series with the buzzer switch 72f to be operated thereby.

A further modification of the invention is shown in FIGS. 33 and 34. This form of the invention incorporates the buzzer type switch, such as in FIG. 32, and similar numerals are used to identify like parts, this time with the addition of the suffix g. The essential difference in the switch 72g is that it incorporates the utilization device, and functions as a peristaltic pump 132. The left half of the switch is the same as in FIG. 32. However, the right half is also of rigid plastic, and is permanently offset or distended. The right-hand contact 52g-R comprises a magnetic strip or diaphragm mounted between the two plastic switch halves and free throughout most of its length. A flexible tube 134 of plastic or rubber material extends re-entrantly through the switch, comprising one leg 136 lying on the left side of the switch contact 52g-R, and a second leg 138 lying on the opposite side of the switch contact, the two legs being adjoined by a bight 140. Action of the switch 72g, as a switch is similar to that of the switch 72f. The magnetic contact 52g-R normally is in contact with the non-ferrous switch contact 52g-L. In this position, it compresses the left tubing leg 136. When the external circuit is closed to energize the coil 126g, the ferrous switch contact 52g-R moves to the right, thereby releasing the left leg 136 and compressing the right tubing leg 138. As will be appreciated from the foregoing description, the switch contact 52g-R oscillates back and forth, alternately compressing the two tubing legs 136 and 138. This produces a pumping action on the well-known peristaltic principle.

A fluid logic circuit 142 is incorporated in the form of the invention illustrated in FIGS. 35 and 36. A flat, plate-like plastic base 144 is provided and has an inlet at 146 which can be diverted either to a left outlet 148 or a right 150 by jets directed in from side control channels 152 or 154, in accordance with known principles of fluid logic circuits. A pillow-type switch 72h of generally the same type heretofore described is incorporated in the outlet 150, having two spaced fixed contacts 156 and 158 capable of being bridged by a shorting bar contact 160, the contacts obviously being mounted on the inner

faces of spaced plastic sheets in accordance with the previous descriptions set forth herein. Wires 162 are connected to the contacts 156. As will be understood, when fluid is diverted to one or the other of the outlets 148, 150, the condition of the switch 72h is reversed. For example, the switch 72h can be of the type which is normally closed. With an unrestricted outlet 150, when fluid is diverted to this outlet, the lateral pressure due to Bernoulli action will be decreased, and the switch will be opened. Conversely, the normally opened switch could be used with an outlet 150 having a restricting orifice connecting it to atmosphere or to exhaust. When fluid is diverted to the outlet 150, a slight external pressure on the switch 72h will cause it to close.

Turning now to FIG. 37, there will be seen a human hand 164 in an air-tight glove 166 for use in a hostile environment, such as in outer space, or beneath the surface of a body of water. Switches 72i in accordance with any of the previous teachings herein, such as the normally opened single-pole, single-throw switches of FIGS. 5-7 are incorporated adjacent the tips of the fingers and thumb of the glove, and are connected to a wiring harness 166. The fingers can be pressed together in various manners to close selected ones of the switches, or the fingers can be pressed against the body or some other part of the environment to close the switches selectively.

It will be apparent from the foregoing that I have disclosed a superior switch which is inexpensive and rugged, and which is readily sealed against the atmosphere or other external environment. The switch is made quite inexpensively by the use of known printed circuit techniques. It is contemplated that the switches need not be made one at a time, but that a great many could be made simultaneously from large sheets of plastic and the switches could then be cut apart by dies.

The specific embodiments of the invention as herein shown and described are for illustrative purposes. Various changes will no doubt occur to those skilled in the art, and will be understood as forming a part of the present invention insofar as they fall within the spirit and scope of the appended claims.

The invention is claimed as follows:

1. An electric switch comprising a pair of single-thickness sections of insulating material at least one of which is resilient and of substantially uniform thickness, said sections being joined together substantially peripherally and having spaced interior areas each of predetermined contours, and at least one conductive element on the internal area of each insulating material section and conforming to the corresponding predetermined contour, said conductive elements being substantially no thicker than the thickness of said resilient insulating material and being flexible therewith, said conductive elements being selectively engageable and non-engageable with one another upon selective deflection of said resilient section of insulating material.

2. An electric switch as set forth in claim 1 wherein the sections of insulating material comprise plastic sheets, and wherein the conductive elements comprise printed circuit conductive elements.

3. An electric switch as set forth in claim 1 wherein both sections of insulating material are flexible, and wherein said conductive elements are strips which partially overlap.

4. An electric switch as set forth in claim 3 wherein the strips are aligned and overlap in end-to-end relation, extending in opposite directions.

5. An electric switch as set forth in claim 3 wherein a strip on one section of insulating material is disposed transversely of an insulating strip on the other section of insulating material.

6. An electric switch as set forth in claim 3 wherein there is a plurality of conductive strips on each section of insulating material.

7. An electric switch as set forth in claim 6 wherein

the strips on one section of insulating material are disposed transverse of the strips on the other section of insulating material, each strip thereby being capable of engaging any of a plurality of opposite strips.

5. An electric switch as set forth in claim 1 wherein the sections are peripherally sealed together with gas trapped therebetween.

9. An electric switch as set forth in claim 1 wherein the two sections of insulating material are substantially sealed together peripherally, there being a restricted aperture in one of said sections throttling air flow in and out of the switch and controlling the movement of said resilient section.

10. An electric switch as set forth in claim 1 wherein both sections of insulating material are resilient, said switch being of pillow-like construction having relatively large opposite faces, said conductive elements being normally spaced apart and brought into engagement by pressure on said faces.

20. An electric switch as set forth in claim 1 wherein both of said sections of insulating material are resilient, the switch being of pillow-like construction having opposite faces and peripheral edges, said conductive elements normally being in engagement with one another and moved out of engagement by opposing pressure on said peripheral edges.

25. An electric switch as set forth in claim 1 wherein both of said sections comprise an integral sheet of plastic material folded over on itself.

30. An electric switch as set forth in claim 12 wherein there are two conductive elements on the internal area of one insulating material section and one conductive element on the other insulating material section serving as a shorting bar for the two conductive elements on the other section.

35. An electric switch as set forth in claim 13 wherein the two sections of insulating material comprise a single sheet of plastic folded over on itself.

40. An electric switch as set forth in claim 1 and further including electromagnetic means for operating said switch.

45. An electric switch as set forth in claim 15 wherein the electromagnetic operating means includes an external plunger engageable with one of said sections of insulating material.

50. An electric switch as set forth in claim 15, wherein one of the conductive elements comprises magnetic material, and further including external magnetic means acting thereon.

55. An electric switch as set forth in claim 18 wherein each section has a plurality of like conductive elements, the conductive elements comprising a plurality of separately actuatable poles, said sections of insulating material being pellucid, and a plurality of lights therebehind corresponding to the respective poles.

60. An electric switch as set forth in claim 1 in combination with a fluid logic circuit having various passageways including discharge passageways, said switch being located in one of said discharge passages and actuated by pressure differential relative to ambient.

65. A plurality of similar switches as set forth in claim 1 in combination with a glove, said switches being mounted adjacent finger positions inside said glove for respective actuation by finger pressure.

70. An electric switch comprising a pair of sections of insulating material, said sections of said insulating material being peripherally joined together, at least one of said sections having an outwardly offset central portion providing spaced, confronting first and second interior areas on said pair of sections, a first electric contact lying on one internal area, a second contact lying between said first contact and said second internal area, said second contact being of magnetic material, and external electromagnetic means acting on said second con-

tact to vary the condition of engagement with said first contact.

22. An electric switch as set forth in claim 21 and further including a loop of resilient tubing having a pair of legs lying on opposite sides of said second contact and alternately compressed between said second contact and said first and second internal areas to produce a pumping action.
